(57) **CLAIM**

The ornamental design for scissors as shown.

DESCRIPTION

FIG. 1 is a first perspective view of scissors showing my new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a third perspective view thereof, showing the scissors in a use state.

The broken lines in the drawings represent the portions of the scissors that form no part of the claimed design.
